UNITED STATES PATENT OFFICE

FELIPE INOCENCIO, OF GLEN DORA, CALIFORNIA

DESIGN FOR A RECEPTACLE COVER

Application filed December 29, 1932. Serial No. 46,653. Term of patent 7 years.

To all whom it may concern:

Be it known that I, FELIPE INOCENCIO, a Filipino, residing at Glendora, in the county of Los Angeles and State of California, have invented a new, original, and ornamental Design for Receptacle Covers, of which the following is a specification, reference being had to the accompanying drawing, forming part thereof.

In the drawing:

Figure 1 is a perspective view of a receptacle cover, showing my new design;
Figure 2 is a plan view;
Figure 3 is a side view; and
Figure 4 is an end view of the same.

I claim:

The ornamental design for a receptacle cover, as shown.

FELIPE INOCENCIO.
